[57] ABSTRACT

A current amplifier comprising first and second series circuits coupled to the emitter and base respectively of a first transistor amplifying received signals to allow accurate adjustment of the current in the first series circuit relative to the current in the second series circuit without increasing the output impedance of the amplifier. The first series circuit comprises a first diode and a second transistor coupling the emitter of the first transistor to the power supply. The second series circuit comprises a second diode, a third transistor, and a current determining means coupling the base of the first transistor to the power supply. The first and second series circuits cooperate to respond to differences in the current in the second series circuit and the current in the first series circuit thereby maintaining predetermined relationships between these currents.

CURRENT AMPLIFIER

The invention relates to a current amplifier in which the signal current is supplied to the base of first transistor from the emitter of which the amplified signal is taken. In a known current amplifier of this type the emitter of the first transistor of the npn type is connected to a supply terminal through the emitter collector path of a second transistor of the pnp type. The base of the first transistor is connected to the same supply terminal through the series combination of two diodes and a current supply source. The base of the second transistor is connected to the terminal of the said current supply source not connected to the supply terminal. In this known current amplifier the quiescent current of the first and second transistors is adjusted by means of the two diodes and the current supply source. The two diodes are traversed by a constant current so that a voltage V_o will be set up across them. Consequently, this voltage is set up between the base of the first transistor and the base of the second transistor. As a result, a current will flow through the first and second transistors which is substantially equal to the constant flowing through the two diodes. If now the voltage V_o varies, for example owing to a variation in temperature, the current flowing through the first and second transistors will remain constant, because the current flowing through the diodes is constant also.

The known current amplifier has the disadvantage that the current flowing through the first and second transistors never can be made exactly equal to the current flowing through the two diodes. This is due to the "early effect" which occurs in transistors. This is due to the fact that the current flowing through a transistor is determined not only by the base emitter voltage of the transistor but also by its collector emitter voltage. The two diodes of the afore-described current amplifier may be regarded as two transistors in each of which the base is directly connected to the collector. This means that the collector emitter voltages of these transistors connected as diodes are equal to zero volt. However, the collector emitter voltage of the first and of the second transistor is equal to one half of the supply voltage applied between the collectors of the first and second transistors. Consequently, the quiescent current flowing through the first and second transistors will be greater than the current flowing through the two diodes, the difference increasing with increase in the applied supply voltage. The afore-described early effect occurs very strongly in horizontal pnp transistors, so that in the known current amplifier the quiescent current may be considerably different from the current through the two diodes. To compensate for this current inequality frequently small resistors are included in the emitter leads of the first and second transistors. A first disadvantage of this arrangement consists in that the output impedance of the current amplifier is increased, and a second disadvantage is that, in driving, the voltage drop across the two resistors alternately cuts off the first and the second transistor, which gives rise to linearity problems at the passages through zero of the amplified signal.

It is an object of the present invention to obviate the said difficulties, and the current amplifier according to the invention is characterized in that the emitter of the first transistor is connected to a supply terminal through the series connection of at least one additional

diode and the emitter collector path of a second transistor and the base of the first transistor is connected to the same supply terminal through the series connection of at least one second diode, the emitter collector path of a third transistor and a current-determining element, the base of the third transistor being connected to the lead connecting the first diode to the emitter of the second transistor, and the base of the second transistor being connected to the lead connecting the third transistor to the current-determining element.

Embodiments of the invention will now be described, by way of example, with reference to the accompanying diagrammatic drawing, in which:

FIG. 1 is the circuit diagram of a current amplifier according to the invention,

FIG. 2 shows another embodiment of the current amplifier according to the invention and,

FIG. 3 shows a quasi pnp transistor.

Referring now to FIG. 1, the collector of a first transistor T_1 is connected to the positive terminal of a voltage supply source E through a resistor R_1 . The emitter of the transistor T_1 is connected through the series combination of a first diode D_1 , the emitter collector path of a second transistor T_2 and a resistor R_2 to the negative terminal of the voltage supply source E . The base of the transistor T_2 is connected to the negative terminal of the voltage supply source E through a current-determining element S . The current-determining element may be a resistor or a current source. The base of the transistor T_1 is connected to the base of the transistor T_2 through a second diode D_2 and the emitter collector path of the third transistor T_3 . The base of the transistor T_3 is connected to the emitter of the transistor T_2 . The base of the transistor T_1 is connected to the emitter of a transistor T_0 connected as an emitter follower. The signal to be amplified may be applied to the base of the transistor T_0 . The amplified signal may be derived from the emitter of the transistor T_1 , for example across the impedance Z , as is shown in this Figure by broken lines.

The operation of the current amplifier according to the invention is as follows. The transistors T_1 , T_2 and T_3 and the diodes D_1 and D_2 form a controlled current source. The measuring diode of this current source is formed by the series combination of the diode D_1 and the base emitter path of the transistor T_1 . The voltage across this measuring diode is equal to the sum of the voltages across the diode D_2 and the base emitter path of the transistor T_3 under any circumstances. The quiescent current flowing through the measuring diode is compared with the current flowing through the current-determining element S . If now the quiescent current through the measuring diode and hence the quiescent current through the two transistors T_1 and T_2 differs from the current flowing through the current-determining element S , the quiescent current is reduced through the collector of the transistor T_3 to the base of the transistor T_2 until the quiescent current through the transistors T_1 and T_2 has again become equal to the current flowing through the current-determining element S . Although the sum of the voltages across the diode D_1 and across the base emitter diode of the transistor T_1 will be constant, the current flowing through the diode D_1 may considerably differ from the

current through the transistor T_1 , i.e. when an output impedance Z is connected between the emitter of the transistor T_1 and a point of constant potential, as is shown in broken lines in FIG. 1. The current through the transistor T_1 will increase with increase in the output voltage at the emitter of the transistor T_1 . Hence, the base emitter voltage of the transistor T_1 increases. Because the sum of the voltages across the diode D_1 and across the base emitter path of the transistor T_1 is constant, the voltage across the diode D_1 will decrease by the same amount by which the voltage across the base emitter diode of the transistor T_1 increases. This means that when the current through the transistor T_1 has become equal to jI , the current through the diode D_1 will be equal to I/j , where I is the current flowing through the current-determining element. If the output signal at the emitter of the transistor T_1 decreases, the reversed effect will occur. However, the current through the transistor T_1 will now decrease with increase of the current through the diode D_1 . The maximum output current which can flow through the load Z is equal to the current I multiplied by the base collector current amplification factor β of the transistor T_2 .

The fact that the base emitter voltage of the transistor T_2 is not one of the factors determining the adjustment of the quiescent current through the transistors T_1 and T_2 has the advantage that the transistor T_2 may simply be replaced by a quasi pnp transistor as shown in FIG. 3. For this purpose, in the circuit arrangement shown in FIG. 1 the transistor T_2 is omitted and terminals A, B and C of the quasi pnp transistor shown in FIG. 3 are connected to corresponding points A, B and C of the circuit arrangement of FIG. 1. The inclusion of the quasi pnp transistor in the circuit arrangement of FIG. 1 provides the advantage that the maximum output current of the current amplifier is increased. This current will now be equal to βI amperes, where β is the base collector current amplification factor of an npn transistor T_{22} of FIG. 3. The current amplification factor β of the transistor T_{22} is much greater than the corresponding current amplification factor of the pnp transistor T_2 of FIG. 1. This replacement is not possible in the known current amplifier described at the beginning of this specification.

Owing to the absence of the resistors in the emitter leads of the transistors T_1 and T_2 the output impedance of the current amplifier shown in FIG. 1 will be several times smaller than the output impedance of the known current amplifier. In addition, the absence of the said resistors results in that neither the transistor T_1 nor the transistor T_2 will ever be cut off by driving, because the current through the transistors T_1 or T_2 logarithmically tends to zero. As a result, compared with the known current amplifier much smaller quiescent currents through the transistors T_1 and T_2 are permissible and moreover far less linearity problems will arise at the passages through zero of the amplified signal.

So far it has been assumed that the quiescent current through the transistors T_1 and T_2 will always have to be equal to the current I flowing through the current-determining element S . Under certain circumstances, for example in respect of bandwidth, stability and current consumption, it may be of advantage to make the quiescent current different from the current I flowing

through the current-determining element S . For this purpose, for example, the emitter area of the transistor T_3 may be made larger than the emitter area of the diode D_2 , and the emitter area of the diode D_1 may be made larger than the emitter area of the transistor T_1 , the quotient of the areas of the diode D_2 and of the transistor T_1 remaining equal to the quotient of the areas of the transistor T_3 and of the diode D_1 .

The resistors R_1 and R_2 may be made equal to zero. This has the advantage that the driving range of the current amplifier will be a maximum.

If the output current is too small, the circuit arrangement of FIG. 1 may simply be expanded, as is shown in FIG. 2. The base of a transistor T_4 is connected to the collector of the transistor T_1 and the emitter of the transistor T_4 is connected to the positive terminal of the voltage supply source E . The base of a transistor T_5 is connected to the collector of the transistor T_2 and the emitter of the transistor T_5 is connected to the negative terminal of the voltage supply source E . The collectors of the transistors T_4 and T_5 are connected to the emitter of the transistor T_1 , which emitter is also connected to a point of constant potential through the output impedance Z . The resistors R_1 and R_2 have been chosen so that for small input signals appearing at the base of the transistor T_0 the two transistors T_4 and T_5 remain cut off. When input signal increases the two transistors T_4 and T_5 will be rendered conductive at a certain instant, because the voltages produced across the resistors R_1 and R_2 have become sufficiently large. At the said instant the total output current is equal to the sum of the currents through the transistors T_1 and T_4 or to the sum of the currents through the transistors T_2 and T_5 . The addition of the currents ensures that the frequency properties of the transistors T_4 and T_5 play no part in determining the transfer characteristic between the input and the output of the current amplifier.

What is claimed is:

1. A current amplifier comprising signal input and output means, a first transistor for amplifying received signals having its base coupled to said signal input means and its emitter coupled to said signal output means, input means for a power supply, the collector of said first transistor being connected to a first terminal of said power supply input means, a first series circuit coupling the emitter of said first transistor to a second terminal of said power supply input means, said first series circuit comprising a first diode and the emitter-collector path of a second transistor, a second series circuit coupling the base of said first transistor to said second terminal of said power supply, said second series circuit comprising a second diode, the emitter-collector path of a third transistor and current determining means, the base of said third transistor being connected to the junction between said first diode and said second transistor and the base of said second transistor being connected to the junction between said third transistor and said current determining means, said first and second series circuits providing means for measuring and adjusting the current in said first series circuit in response to deviations thereof to maintain predetermined current relationships with the current in said second series circuit.

2. A current amplifier as claimed in claim 1 further comprising a resistor coupling the collector of said second transistor to said second terminal of said power supply input means, and a fourth transistor of the type having a larger base to emitter amplification factor than that of said second transistor for cooperating with said second transistor to increase the output current of said current amplifier, the collector of said fourth transistor being connected to the emitter of said second transistor, the base of said fourth transistor being connected to the collector of said second transistor, and

the emitter of said fourth transistor being connected to said second terminal of said power supply input means.

3. A current amplifier as claimed in claim 1 wherein resistors are arranged between the collectors of the first and second transistors and the terminals of said power supply input means.

4. A current amplifier as claimed in claim 3 wherein said resistors are each shunted by the base emitter path of a transistor having its collector connected to the emitter of said first transistor.
